UNITED STATES PATENT OFFICE.

GEORGE S. BENNETT, OF SAN FRANCISCO, CALIFORNIA.

OIL-REGULATING VALVE.

No. 868,757.

Specification of Letters Patent.

Patented Oct. 22, 1907.

Application filed October 1, 1906. Serial No. 336,834.

To all whom it may concern:

Be it known that I, GEORGE S. BENNETT, a citizen of the United States, residing in the city and county of San Francisco and State of California, have invented 5 certain new and useful Improvements in Oil-Regulating Valves, of which the following is a specification.

My invention relates to oil regulating valves, although, of course, the valve may be used to regulate the flow of any fluid, other than oil, where there is considerable wear on the valve parts.

In the feeding of fuel oil to burners it is very essential that a fixed small quantity of oil be fed continuously, and this is often accomplished by means of needle or other valves, having at the minimum feed 15 point substantially the same area of valve seat surface exposed to the wear of the moving fluid as at points of greater feed. The result of this is that when small quantities of oil are to be fed to the furnace the valve must be nearly closed, but since the oil nearly always 20 contains more or less grit the wear on the valve seat becomes a serious matter. The form of opening left at this time with the needle valve is similar to an annulus, but it is such a thin annulus that the oil very easily gums the opening up, and the grit in the oil 25 closes the opening nearly as easily, making it very difficult to feed a regular amount of oil. Then as the wear comes directly on the valve seat it is only a short time till the valve must be reground to prevent leakage; and in the case of valves of other types where it is 30 sought to reduce the area of valve seat material in contact with the oil in proportion to the reduced amount of oil to be fed the valve seat is adjacent the valve opening bringing the wear over the valve seat that must finally close the opening entirely. This causes 35 the valve seat to wear on one side more than on the side not exposed to the swift flow of the oil and the uneven wear soon causes the valve to leak. The only remedy in these cases is to reground the valve seat and the valve stem.

40 These various defects are overcome in the present invention by concentrating the oil feed in a small aperture having at all times as small a valve surface circumscribing the aperture as it is convenient to make. There is in this valve a much smaller surface to wear 45 than in the needle valve of the same capacity. The tendency of the fast moving oil to wear the valve seat is removed by making the regulating opening and the closing opening sufficiently distant from each other to allow the opening at the valve seat to be entirely open, 50 before the small regulated stream begins to feed. The consequence of this is that the flow of oil at the valve seat is very much slower than the flow of the oil at the regulating opening, and the wear at the latter point is for the same reason very much less.

55 In the drawings which form a part of this specification, and in which like numerals denote like parts;

Figure 1 is a side view of the valve, Fig. 2 is a section of the valve in a plane parallel to the plane of view of Fig. 1, Figs. 3, 4 and 5 are views showing a cross section of the valve stem at the different points indicated by the dotted lines *x*, *y* and *z* on Fig. 2.

The numeral 1 denotes the valve stem, 2 the body of the valve, 8 the packing cap and 9 the threads with which the valve stem may be pressed into contact with the valve seat 3. The bottom of the stem has a seat 4 ground on it to match the seat on the body of the valve. Inside the valve body there is a flange or diaphragm 5 which fits the stem quite closely, but within which the stem is free to slide. This flange or diaphragm 5 fits the stem 1 so closely as to prevent all but an inappreciable quantity of oil from going between it and the stem, except when the cut 6 is in such a position as it is intended to feed oil. The cut 6 on the side of the valve stem is at such a height with respect to the end of the stem that is ground to a seat at 3, and the flange 5 that 70 the stem may rise to a full opening at 3, 4, without the cut 6 allowing any oil to escape. The valve stem is threaded into the screw plug 10 at 9, and the screw plug 10 has a stuffing box with a cap 8. The screw plug 10 must be of such a length that the ring 7 on the valve 75 stem will seat against it to prevent the stem from rising too high and again reducing the flow of the oil.

The regulated feed of the oil begins when the cut 6 rises out of the flange 5, and at first the cut is very small, as indicated at 6 in Fig. 3. The area of the cut increases as shown in Figs. 4 and 5, so that as the valve rises to those points the flow of oil increases.

It will be seen that the flow of the oil is regulated by a part of the valve not directly related to that part of the valve intended to entirely cut off the flow, so that 90 any wear that may occur at the point of regulation is of little consequence, and does not affect the capability of the valve to deliver a regulated stream of oil. Whatever wear the cut 6 may be subject to does not affect the valve seat for it is at a full opening at that time, 95 and it is not likely to wear to such an extent that it will allow oil to escape when the valve stem is nearly down, but should it do so all that is necessary is to take out the valve stem 1 and reground it, taking care to make the new surfaces no deeper in the stem than is necessary 100 to cause the cut to be below the flange 5 when the stem is seated on the valve body at 4.

This valve possesses the advantage of two valves, one of which is used solely to regulate the flow of the fluid, and the other to entirely cut off the supply, and it is 105 better than two valves for the reason that the regulation and closure are accomplished by operating the same stem. It has the further advantage that the flange 5 holds the stem in place over the center of the valve seat, so that nothing short of a very serious bending of 110 the valve stem would prevent it from seating properly.

The shape of the cut 6 is entirely immaterial, it only

being essential that when the valve stem 1 is about to seat on the valve body 2 that the feed shall be substantially cut off by the flange 5, and that the cut 6 shall be of a variable cross-sectional area in order that the regulation may be accomplished.

Without limiting myself to the precise structure shown, since there may be slight changes therein without departing from the spirit of the claims presented, I claim and desire to secure by Letters Patent of the 10 United States the following:

- 15 1. In a regulating valve, the combination of a valve body having a seat therein, a valve stem having a seat at its end and means to regulate the flow of fluid when the valve is full open at the valve seat, and a flange on the valve body above the valve seat within which the valve stem slides, substantially as described.
- 20 2. In a regulating valve, the combination of a valve body having a seat therein, a flange projecting from the interior of the body and closely surrounding the valve stem, a valve stem having a seat at its end and a regulating cut of variable cross area at such a height above the end of the stem as to completely open only when the valve is full open at the valve seat, and means to press the stem against the seat, substantially as described.
- 25 3. In a regulating valve, the combination of a valve body having a valve seat within the same, a flange projecting from the interior of the valve body and closely surrounding the valve stem, a valve stem having a seat at its end and a regulating cut at such height above the end of the valve stem as to open communication between the valve ports only when the valve is wide open at the valve seat, means to press the valve against the valve seat and means to prevent the stem from being raised too high, substantially as described.
- 30 4. In a regulating valve, the combination of a valve body having a valve seat within the same, a flange pro-

jecting from the interior of the valve body and closely surrounding the valve stem, a valve stem having a seat at its end and a regulating cut at such a height above the end of the valve stem as to begin to open only when the opening at the valve seat is wide open, and means to press the valve stem against the valve body, substantially as described.

5. In a regulating valve, the combination of a valve body having a seat therein, a valve stem having a seat at its end and a cut near the seat end of the valve stem, a diaphragm within the valve body and within which the valve stem slides freely, and a ring on the valve stem to prevent it from being raised too high, substantially as described.

6. In a regulating valve, the combination of a valve body having a valve seat therein, a valve stem having a seat at its end adapted to be pressed against the valve seat and being cut away above the end thereof the cut extending longitudinally of the valve stem and being of less cross sectional area at its top than at points lower down, a ring surrounding the valve stem and means to prevent the stem from being raised too high, substantially as described.

7. In a regulating valve, the combination of a valve body having a seat therein; a valve stem having a seat on its end to match the body seat and a regulating cut in its side above the stem seat; a flange extending from the valve body and closely surrounding the valve stem, the valve being of greater cross sectional opening between the seat and the flange than the valve stem, substantially as described.

In witness whereof I have hereunto subscribed my name in the presence of two witnesses this 24 day of September, 1906.

GEO. S. BENNETT.
